Primary Examiner—Doris V. Coles*Attorney, Agent, or Firm*—Kolisch, Hartwell, Dickinson, McCormack & Heuser[57] **CLAIM**

The ornamental design for a diving fishing weight, as shown and described.

DESCRIPTION

FIG. 1 is a perspective view of a diving fishing weight, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a perspective view of the second embodiment;
FIG. 9 is a front elevational view thereof;
FIG. 10 is a rear elevational view thereof;
FIG. 11 is a top plan view thereof;
FIG. 12 is a bottom plan view thereof;
FIG. 13 is a left side elevational view thereof;
FIG. 14 is a right side elevational view thereof;
FIG. 15 is a perspective view of a third embodiment;
FIG. 16 is a front elevational view thereof;
FIG. 17 is a rear elevational view thereof;
FIG. 18 is a top plan view thereof;
FIG. 19 is a bottom plan view thereof;
FIG. 20 is a left side elevational view thereof;

FIG. 21 is a right side elevational view thereof;
FIG. 22 is a perspective view of a fourth embodiment;
FIG. 23 is a front elevational view thereof;
FIG. 24 is a rear elevational view thereof;
FIG. 25 is a top plan view thereof;
FIG. 26 is a bottom plan view thereof;
FIG. 27 is a left side elevational view thereof; and,
FIG. 28 is a right side elevational view thereof.
The broken line showing of environment in FIGS. 1, 8, 15
and 22 is for illustrative purposes only and forms no part of
claimed design.
